UNITED STATES PATENT OFFICE.

FRITZ SCHMIDT, OF NEW YORK, N. Y.

DESIGN FOR A GLOVE.

SPECIFICATION forming part of Design No. 36,665, dated December 1, 1903.

Application filed October 2, 1903. Serial No. 175,530. Term of patent 7 years.

To all whom it may concern:

Be it known that I, FRITZ SCHMIDT, a citizen of the United States, and a resident of the city of New York, borough of Manhattan, in the county and State of New York, have invented a new, original, and ornamental Design for a Glove, reference being had to the drawing, in which the figure is a perspective view of a glove, showing my ornamental design.

I claim as new and desire to secure by Letters Patent—

The ornamental design for a glove, substantially as herein illustrated.

In testimony whereof I have signed my name to this specification in the presence of two subscribing witnesses.

FRITZ SCHMIDT.
